UNITED STATES PATENT OFFICE

2,488,800

DEVICE FOR HEATING LARGE ROOMS

Henri Borghesan, Nice, France

Application January 3, 1946, Serial No. 638,877
In France January 5, 1945

2 Claims. (Cl. 237—8)

1

It is known that the heating of spacious rooms such as the halls and workshops of modern factories, for example, involves serious difficulties. Many systems have been proposed for this heating but none of them has been able, up to the present, to give the workers the comfort which enables them to work with utmost efficiency.

Among these systems, those which have given the best results, without attaining however the proposed goal, are the heating system by warm air blown into the room to be heated at the height of a man and withdrawal of the cold air at floor level, and the system which consists in heating the floor by means of heating panels constituting the whole or a part of the floor of the workshop. The first of these systems effectively heats the upper part of the worker's body, but his feet and legs remain cold. Furthermore, a considerable part of the heat is lost under the roof, without any advantage for the occupant. With the second of the above mentioned systems, the worker's feet and body are warm and the heat is distributed to points where it is the most needed, resulting in much better conditions of comfort and hygiene than those provided by other systems. It has however been noticed that in very cold weather the convection currents attain such proportions that the air which has been cooled while descending along the walls, from the higher to the lower parts of the workshop, reach the persons who are located therein. This fact causes considerable discomfort. Furthermore, if the heating panels cover only a part of the floor, movements of cold air coming from the roof and from the walls are caused between the unheated places and the roof. Under these conditions, it is undesirable to stay in any part of the workshop.

This invention avoids the mentioned drawbacks by means of a particular combination of the heating system by blown warm air and the floor heating system.

It consists substantially in a plant comprising at the same time one or more warm air blowing devices above the occupants of the rooms to be heated and floor heating panels, combined with means for putting the first named devices into action only in case of very cold weather, so that the air blown by these devices forms a protective screen preventing the fall of cold air.

An embodiment of the invention may further be characterized by the use of one or more devices comprising on the one hand a lower air intake opening, a ventilator driving the air through a heater connected to an upper chamber

2

having blowing openings on one or several sides and, on the other hand, a circulation pump having an intake fitting and driving a liquid through a heat exchanger the other end of which is connected to another fitting, these two fittings allowing the device to be connected to the head panel of the floor heating panel system, the air heater and the heat exchanger being provided with means for connection to a heating liquid distributing system, manually or thermostatically controlled valves being interposed. A motor drives the ventilator and pump, together or separately, by means of clutches.

Figs. 1 and 2 show schematically the operation of heating plant according to this invention, two main arrangements being illustrated.

P are the floor heating panels and S is an air blowing device for hot air. It may be seen that the blown air forms a protective layer E which arrests the current of cold air C descending from the roof, along the walls of the workshop.

Fig. 3 is a schematic vertical section of a combined device which may be used in a preferred embodiment of the plant according to the invention.

Fig. 4 is an external perspective view of the same device, in a slightly different embodiment.

1 is a body of sheet metal of a convenient form, 2 is a centrifugal or helical ventilator, 3 is an electric motor driving the ventilator, 4 is a clutch for connecting and disconnecting the ventilator and motor, 5 is an air heater through which the ventilator drives the air, and 6 is an upper chamber provided with blowing openings 7 on one or several sides.

On the other hand, 8 is a pump driven by the motor 3 through a clutch 4¹ and the intake of which can be connected by a pipe and fitting 9 to the outflow of a head panel P¹ feeding all the floor heating panels. This pump drives its contents into a heat exchanger 10 the outflow of which can be connected, by a tube and fitting 11, to the intake of the said panel P¹. 12 is an expansion receiver.

A distributing system 13 feeds the heating fluid (electricity, hot water, steam, etc.) to the heater 5 and exchanger 10, through valves 14 and 15 respectively, controlled by hand or by thermostats Th, Th'.

The device operates as follows:

When the outer temperature is moderately cold, the heating fluid enters only through the valve 15 into the heat exchanger 10 where it heats the water of the panels P which circulates

under the action of the pump 8 working alone. In this case, the heating is thus effected only by the panels P.

When the external temperature descends below a predetermined value, causing the cold air currents in the heated rooms to descend, the valve 14 is opened by hand or by the thermostat Th and the ventilator 2 is started by throwing in the clutch 4. From that moment on, the warm air screens E arrests this downflow of cold air above the heads of the occupants who continue to be normally heated by the panels P.

The device shown in Figs. 3 and 4 is preferably designated so as to be easily dismountable and it will be possible to transport it in order to use it in different points where connections to the supply 13 and a head panel P¹ are provided, the unused connections being closed and the fittings of the unused panels P¹ being connected together by a pipe. It is of course possible to use several devices at the same time, at different points of the hall or workshop to be heated.

What I claim is:

1. A transportable heating unit for spacious rooms equipped with a heating fluid supply and with floor heating panels containing heating coils, comprising a lower air intake, an air heater, an upper chamber formed with at least one opening for the ejection of a horizontal screen of air just above a man's height, a ventilator driving air from said intake through said air heater into said upper chamber, a pump, a heat exchanger,

a tubular circuit passing through said pump and said heat exchanger, means for detachably connecting said tubular circuit to the heating coils of said floor heating panels, disconnectable means for connecting said air heater and said heat exchanger to said heating fluid supply, a motor driving said ventilator and said pump, a first clutch between said motor and said ventilator, and a second clutch between said motor and said pump.

2. A transportable heating unit as claimed in claim 1, comprising a thermostatic control for said disconnectable means.

HENRI BORGHESAN.
